UNITED STATES PATENT OFFICE.

JOHN C. PREWITT AND CLARK HENDRICKS, OF SANTA MARGARITA, CALIFORNIA.

WINDMILL.

1,221,090.

Specification of Letters Patent.

Patented Apr. 3, 1917.

Application filed March 11, 1916. Serial No. 83,507.

To all whom it may concern:

Be it known that we, JOHN C. PREWITT and CLARK HENDRICKS, citizens of the United States, residing at Santa Margarita, 5 in the county of San Luis Obispo and State of California, have invented new and useful Improvements in Windmills, of which the following is a specification.

This invention relates to a wind mill.

10 One of the objects of the present invention is to provide a simple, rigid, easily operated wind mill, which consists of a horizontally positioned oscillating beam, carrying a sail frame at one end and an adjustable counter-weight at the other end.

Another object of the invention is to provide means for holding the beam and sail frame in trailing position in the wind, and furthermore, to provide means for automatically 20 rocking the sail frame at the end of each stroke to change the angle of the sails and the direction of the movement of the beam.

Another object is to either transmit the 25 power created by the oscillating movement of the beam in such a manner that it may be used for pumping water or operating other machinery used on the farm or in other places. Further objects will hereinafter appear.

The invention consists of the parts and the construction and combination of parts, as hereinafter more fully described and claimed, having reference to the accompanying 35 drawings, in which—

Figure 1 is a side elevation of the wind mill.

Fig. 2 is an enlarged cross section on line 2—2, Fig. 1.

40 Fig. 3 is an enlarged detail view in side elevation of one tilted position of the track members.

Referring to the drawings in detail, A indicates a suitably shaped support on the 45 upper end of which is turnably mounted a head 2, provided with a pair of rearwardly extending fork-shaped bracket arms 3. Pivotedly mounted between the arms 3 is an arm or beam 4, on one end of which is mounted an adjustable counter-weight 5. Pivotedly mounted on the opposite end of the beam 4, as at 6 is a sail frame 7 in which is rigidly secured a plurality of sails or planes 8. The planes are lowered at right angles to the frame 7 and can only assume

an angular position with relation to the wind which is supposed to be blowing in the direction of arrows *a*, by tilting the frame about its pivot 6. This is accomplished automatically at the end of each 60 stroke and will be later described.

Secured to the beam 4 just above the fulcrum point of same is a track member 9 and pivotally mounted between the arms 3, as at 10 is a track member 11, which is connected 65 with the upper track 9 by means of a pair of cross links 12. Movement of the beam 4 to assume the dotted line position shown at 14 or 15 causes the track member 11 to assume an opposite angle, this movement being transmitted from the upper track by means of the cross links 12. The tracks will thus always assume opposite angular positions during the movement of the main beam 4, except when this stands in the horizontal 70 position shown. These angular positions of the tracks are of great importance as they provide means for tilting the sail frame at each end of the oscillating movement of the beam 4.

Carried by the track 9 is a weighted roller 16, the movements of which are limited by means of stops 17 formed at each end of the track, and similarly mounted on the track 11 is a weighted roller 18, the 85 movements of which are limited by stops 19. Pivotally connecting the upper roller 16 with the sail frame is a link 20 and similarly connecting the lower roller of the sail frame is a link 21. The operation of 90 the device will be as follows:

The counter-weight 5 is normally adjusted to permit the beam 4 to assume the dotted line position, indicated at 15, when the velocity of the wind is not sufficient to operate the mill. The sail frame will at the same time assume the dotted line position indicated at 7^a. The positions of the planes or sails 8 are such that the wind will strike the planes on their lower surfaces, indicated at 25. The wind pressure thus exerted will raise the sail frame with connected beam 4 about its fulcrum point until the beam reaches the dotted line position, shown at 14. The position of the sail frame 100 is here automatically changed from the dotted line position shown at 7^a to that indicated at 7^b and this is accomplished as 105 follows:

The track member 9 assumes the same 110

tilted position as the beam 4, while the connected cross links 12 will cause the track member 11 to assume the tilted position opposite to that assumed by the track 12. The 5 weighted roller 16 will thus have a tendency to run down the track until it engages with the stop at the lower end, while the roller 18 will run down the track 11 in the opposite direction until it reaches the opposite end 10 of the stop 19. This movement of the rollers in the opposite direction is transmitted through the links 20 and 21 to rock the sail frame about its pivot 6, and this is only accomplished when the beam assumes the 15 angular positions shown at 14 and 15, as the inclined positions of the track members 9 and 11 are not sufficient to permit the rollers to overcome the weight of the sail frame until such positions are assumed by the 20 beam 4. The movement of the sail frame when the beam assumes the dotted line position indicated at 14 from the position 7^b to that assumed at 7^c immediately presents the upper surfaces 26 of the sails to the wind. 25 All pressure is thus exerted at the downward direction, causing the beam to move from the position 14 to that shown at 15. The angular position of the track members will again be gradually changed during the 30 movement of the beam and they will become sufficiently inclined when the position 15 is reached to permit the rollers to run down and again change the position of the sail frame to that indicated at 7^a. Means have also been provided for the purpose of 35 limiting the oscillating movement of the main beam, and also for the purpose of limiting the angular movement of the sail frame. This is accomplished by providing 40 an arm 30 which is pivotally mounted, as at 31 upon a pair of standards 32 carried by the head 3. One end of the arm 30 is provided with a wind vane 33 and the opposite end is provided with a V-shaped head 34, 45 the lower ends of which are adapted to engage projecting pins 35 formed on the upper roller 16. The moment the wind reaches a predetermined velocity it can easily be seen that the pressure exerted 50 against the vane 33 will be sufficient to move the arm from the position shown in Fig. 2 to a point where the lower ends of the head 34 will move into the path of travel of the roller 16, as shown in Fig. 1. 55 The projecting pins 35 will thus be engaged by the head 34 and the movement of the roller limited. The angular position of the sail frame is thus limited and as this controls the movement of the main beam, it can be seen that the oscillating movement will 60 gradually decrease as the wind pressure exceeds the danger point.

A mill constructed as here shown may be used for a great variety of purposes, but is particularly intended for operating plun-

ger pumps. This is accomplished by connecting the sucker rod 40 of the pump with the beam 4 by means of connecting links 41. The oscillating movement of the beam is thus transmitted to raise and lower 70 the sucker rod 40 and is thus ideal for pumping purposes around farms and arid regions. It is obvious, however, that the oscillating movement created may be converted into rotary or any movement desired 75 and can thus be employed for a great variety of purposes.

The materials and finish of the several parts of the device may otherwise be such as the judgment and experience of the 80 manufacturer may dictate.

We wish it understood that various changes in form, proportions and minor details of construction may be resorted to within the scope of the appended claims, and that we do not wish to limit ourselves 85 to the specific design and construction here shown.

Having thus described our invention, what we claim and desire to secure by Letters Pat- 90

1. The combination with the walking beam and the pivotally supported sail frame mounted thereon, of means for automatically 95 tilting the sail frame the moment the walking beam assumes a predetermined angle, said means including rods having one end of each connected with the sail frame at points above and below the pivot, tiltable tracks upon which the opposite ends of the rods are movable, diagonal links connecting the tracks to tilt them simultaneously, and a device for limiting the tilting movement.

2. The combination with a support, of a rotary head on the support, an arm pivotally mounted in said head, a sail frame pivotally mounted on one end of the arm, a counterweight on the opposite end of the arm, a plurality of sails rigidly secured in the sail frame, a track member secured to the arm, a second track member pivotally mounted below the arm, crossed links connecting the track members, a weighted roller mounted on each track member, and a link connecting each roller with the sail frame to 100 automatically tilt the frame when predetermined positions of the arm are reached.

3. The combination with a support, of a rotary head on the support, an arm pivotally mounted in said head, a sail frame pivotally mounted on one end of the arm, a counterweight on the opposite end of the arm, a plurality of sails rigidly secured in the sail frame, a track member secured to the arm, a second track member pivotally 110 mounted below the arm, crossed links connecting the track members, a weighted roller mounted on each track member, a link connecting each roller with the sail frame to 115 automatically tilt the frame when prede- 120 termined positions of the arm are reached.

terminated positions of the arm are reached, and means for limiting the tilting movement of the sail frame.

4. The combination with a support, of a 5 rotary head on the support, an arm pivotally mounted in said head, a sail frame pivotally mounted on one end of the arm, a counterweight on the opposite end of the arm, a plurality of sails rigidly secured in 10 the sail frame, a track member secured to the arm, a second track member pivotally mounted below the arm, crossed links connecting the track members, a weighted roller mounted on each track member, a link connecting each roller with the sail frame to 15

automatically tilt the frame when predetermined positions of the arm are reached, a governor arm pivotally mounted above the main arm, a wind vane on one end of the governor arm, and a V-shaped projection on 20 the other end of the arm engageable with one of the rollers to limit their movement.

In testimony whereof we have hereunto set our hands in the presence of two subscribing witnesses.

JOHN C. PREWITT.
CLARK HENDRICKS.
